UNITED STATES PATENT OFFICE.

JANOS TÁLOS, OF AKRON, OHIO.

LIFE-SAVING SUIT.

1,350,950.

Specification of Letters Patent. Patented Aug. 24, 1920.

Application filed April 26, 1920. Serial No. 376,704.

To all whom it may concern:

Be it known that I, JANOS TÁLOS, a citizen of Hungary, residing at Akron, in the county of Summit and State of Ohio, have invented 5 new and useful Improvements in Life-Saving Suits, of which the following is a specification.

This invention comprehends the provision of a life saving garment, which may be made 10 in one piece or in two separate parts, the garment being adjustable to accommodate persons of different size, and designed to possess maximum buoyancy for the purpose intended. 15 The nature and advantages of the invention will be better understood when the following detail description is taken in connection with the accompanying drawings, the invention residing in the construction, combination and arrangement of parts as claimed. 20

In the drawings forming part of this application, like numerals of reference indicate similar parts in their several views and 25 therein—

Figure 1 is a view in elevation of the garment made up of separate pieces.

Fig. 2 is a transverse sectional view taken on line 2—2 of Fig. 1.

30 Fig. 3 is a similar view taken on line 3—3 of Fig. 1.

Fig. 4 is a view of the garment made in one piece.

Fig. 5 is a sectional view taken on line 5—5 of Fig. 4.

Referring to the drawings in detail and particularly to Figs. 1 to 3 inclusive, A indicates generally the top part of the garment, while B indicates generally the trousers or 40 lower part thereof. The upper part A is constructed from suitable water-proof material, and is designed to slip over the head of the wearer when its use is desired. The upper part A is provided with a neck opening 45 10 and arm openings 11. The opening 10 may be varied in size in any suitable manner, while provided for each arm and on each sleeve, is a strap 14 secured to the sleeve at a point in its length, the strap being provided 50 with a buckle 15 so that each sleeve can be contracted at its free ends about the arm of the user. The lower end of the part A of the garment is also equipped with a belt 16, this end being very wide but susceptible of 55 being contracted to accommodate itself to the user through the instrumentality of the

belt 16. Disposed longitudinally of the part A and coextensive in length therewith, is a plurality of pockets 18 constructed from the same material from which the part A is 60 formed. These pockets may be of any desired configuration in cross section, but are preferably tapered from their lower to their upper ends. Each pocket 18 is adapted to be filled with a buoyant element, which may be 65 cork or any other suitable material indicated at 19.

The lower part of the garment indicated at B is in the form of pants or trousers, wherein the leg portions 20 are comparatively short. 70 The waist portion of the trousers is very wide, and may be adjusted to accommodate the wearer through the instrumentality of a strap 22 provided with a buckle 23. The lower portion of each pants leg is equipped 75 with a strap 24 by means of which the lower edges of the pants may be contracted about the leg of the wearer. The member B is formed from suitable water-proof material and is provided with a plurality of pockets 80 25, similar to the pockets 18 hereinabove described. These pockets 25 are filled with a buoyant agent, of any suitable character such as described in connection with the pockets 18. The garment in its entirety, affords 85 maximum buoyancy to the wearer and is of such a construction that it can be readily and quickly applied and adjusted to the comfort of the user.

In Figs. 4 and 5 I have illustrated a modified form of the invention, or have shown the invention embodied in a garment formed of one piece. The garment indicated at 26 is formed from a single piece of water-proof material of any desired size, bifurcated as at 90 26 to provide leg receiving portions 27, the garment being provided with a neck receiving portion 28 and short sleeves 29. The leg receiving portion as well as the sleeves and neck portion can be contracted about the body 100 of the user by means of straps 30 secured to the parts as shown. The garment in this form of the invention is also designed to provide a plurality of pockets 32 which may be of any suitable length in cross section configuration, 105 the pockets being adapted to be filled with a buoyant agent, such as air, cork, or other material as indicated at 33. This garment may be also quickly and easily applied for use, and affords all of the desired buoyancy 110 for the purpose intended. While it is believed that from the foregoing description

the advantages of the invention will be readily apparent, I desire to have it understood that I do not limit myself in this connection, and such changes may be resorted to when desired as fall within the scope of what is claimed.

What I claim is:

1. A garment of the character described and constructed from water-proof material and including a body portion, legs, arms, and neck receiving portions, means for contacting such portions about the body of the user, a plurality of spaced pockets extending from the neck portion to within a short distance of the ends of the leg portions, and a buoyant

element filling each pocket for the purpose specified.

2. A garment of the character described constructed from water-proof material and including a body portion, legs, arms, and neck receiving portions, spaced longitudinally disposed pockets substantially co-extensive in length with the length of the garment and extending from the neck portion thereof, said pockets being tapered from a point in their length toward their ends, and a buoyant element filling each pocket for the purpose specified.

In testimony whereof I affix my signature.

JANOS TÁLOS.
